TROUSER HANGER

Edwin T. McNutt, Jr., Darlington, Md.

Application April 18, 1946, Serial No. 663,013

3 Claims. (Cl. 223—95)

1

My invention relates to hangers for trousers. In particular, it relates to hangers for supporting trousers by engagement with the cuffs thereof.

An object of my invention is to provide a trousers hanger which is simple in construction and which will support a pair of trousers in a flat condition so as to preserve the press or crease of the trousers.

Another object is to devise a trousers hanger having parts which engage in the folds of the cuffs of the trousers, the parts being so arranged that they will not damage the material of the trousers.

A further object is to devise a trousers hanger in which the weight of the trousers upon the hanger tends to spread the supporting parts of the hanger and maintain the cuffs of the trousers under tension.

A further object of the invention is to devise a trousers hanger which may be folded into a small space when not in use.

My invention is illustrated in the accompanying drawing in which:

Figure 1 is a perspective view of the preferred form of my invention;

Figure 1a is a view on a reduced scale for illustrating the method of forming the hanger of Figure 1;

Figure 2 is an enlarged fragmentary view showing the lower central part of Figure 1 in side elevation;

Figure 3 is a sectional view of Figure 2 taken along the line 3—3;

Figure 4 is a transverse sectional view showing one end of the hanger engaging the cuffs on the two legs of a pair of trousers;

Figure 5 is a perspective view of another embodiment of my invention;

Figure 6 is a side view showing the hanger of Figure 5 in folded position;

Figure 7 is a transverse sectional view of Figure 5 showing one end of the hanger engaging the cuffs on the two legs of a pair of trousers; and

Figure 8 is a fragmentary sectional view taken along line 8—8 of Figure 6.

As shown in the drawing, the preferred embodiment of my invention is formed of a single piece of spring wire, such as spring-steel wire or spring-brass wire. In forming the hanger, a suitable length of spring wire is bent at the middle so that the two halves of the wire 10a and 10b lie parallel to each other and a loop is formed at 10. Figure 1a. The ends of the parallel strands 10a and 10b are bent back on each other as shown at 10a' and 10b' to form two additional loops 11 and 12, and the extreme ends of wire sections 10a' and 10b' are crossed over the wires 10a and 10b at a point spaced from loop 10 about one-third of the distance between this loop and loops 11 and 12, as shown at 10a'' and 10b''. The end portions 5 of these wires are now twisted about wires 10a and 10b to form a twisted section as shown at 10c, Figure 1. If desired, the upper portion of wires 10a and 10b may be twisted together with end portions 10a'' and 10b''.

10 The parallel wires 10b and 10b', forming the loop 10, and the twisted portion 10c, constitute a vertical shank portion of the hanger, and the upper end of this loop is formed into a hook portion 10d which may be hooked over any suitable support.

15 The parallel wires 10a and 10a' forming loop 11 are bent into the shape shown in Figure 1 where the end section 11a extends in a vertical direction, the intermediate section 11b extends in a horizontal direction approximately level with the lower end of the hook portion 10d, and the section 11c extends inwardly and downwardly to a point below the twisted portion 10c. The section 11c may go directly to the lower end of the 20 twisted portion 10c but, for the purpose of adding resiliency to the hanger arm, I prefer to interpose a three-quarter turn loop 11d between the section 11c and the twisted shank portion 10c.

25 The parallel wires 10b and 10b' forming the loop 12 are bent in a similar manner to form an arm extending in the opposite direction from the central vertical shank and consisting of a vertical section 12a, a horizontal section 12b, an inclined section 12c and a loop section 12d.

30 Where greater resiliency in the arms of the hanger is required, the loops 11d and 12d may be formed of more than one turn.

35 From the foregoing it will be seen that each of the two oppositely extending arms of the hanger is formed of parallel wires which constitute two parallel inverted V-shaped frames which 40 may be inserted in the folds of the cuffs on the two legs of a pair of trousers, as will be seen in Figure 4. This figure is a sectional view on a somewhat larger scale than Figure 1, showing how the two frames formed of wire sections 10b and 10b' joined by loop 12 engage the inner folds of the cuffs of the two legs Ta and Tb of a pair of trousers. The vertical sections 11a and 12a 45 are of a length somewhat greater than the width of the cuff on the trousers, so that these vertical sections extend from the bottom of the fold beyond the edge of the cuff. The horizontal sections 11b and 12b engage the inner edge of the bottom fold of the cuffs and serve as sup-

porting sections for the trousers. These sections are of appreciable length so there will be no tendency for the frames to puncture the material of the trousers or to distort the material while the trousers are suspended on the frames. Since the weight of the trousers is carried by the horizontal sections 11b and 12b, the two arms of the hanger will tend to rotate in opposite directions about the lower end of the twisted portion 10c, thereby causing the vertical sections 11a and 12a to spread apart so that these vertical sections will engage against the inner edges of the vertical folds of the cuffs and maintain the cuffs under tension. This action tends to maintain the trousers in properly creased condition. In order to insure the spreading of the arms as described above, the point of attachment of the upwardly and outwardly extending portions of the two arms to the central vertical shank of the hanger should be below the cuffs. As shown in Figure 1, this point is at the lower end of the twisted portion 10c which is located below the loops 11 and 12.

In the modified arrangement shown in Figures 5 to 8, the hanger is formed in a similar manner by bending a length of spring wire at the middle so that the two halves of the wire lie parallel to each other. The looped end of the parallel strands is then bent to form a supporting hook A as shown in Figure 5. Immediately below the hook, the parallel wires are twisted together as at B, and below this the wires are formed into small loops Ca and Cb extending outwardly and transversely of the plane of the hook A. Below these hooked loops, the two wires are again twisted together as at Da and then extend downwardly to form a vertical shank D to the point Db where they are again twisted together, and below this the two wires are coiled in opposite directions to form coil-spring sections Ea and Eb arranged substantially parallel to the plane of the hook A. From these coil sections, the wires extend outwardly and somewhat upwardly in opposite directions, forming arms Fa and Fb. The wire forming arm Fa is extended upwardly to form portion 1a, then horizontally to form section 2a, then vertically downward to form section 3a, looped back at a and vertically up to form section 4a, then horizontally to form section 5a parallel to section 2a, then vertically downward to form section 6a parallel with section 1a, and the lower end of section 6a is twisted about the arm Fa as shown. In a similar manner, the outer end of the wire of arm Fb is bent to form a similar arrangement consisting of sections 1b, 2b, 3b, 4b, 5b and 6b.

As will be seen from Figure 5, sections 1a, 2a, and 3a form a vertical frame of generally rectangular shape while sections 4a, 5a and 6a form a second vertical frame arranged parallel to the frame 1a-2a-3a and of the same shape, and these two frames are supported on the outer end of the arm Fa. A similar pair of parallel rectangular frames 1b-2b-3b and 4b-5b-6b are supported at the end of arm Fb. These frames are inserted in the folds of the cuffs on the two legs of the trousers, as will be seen in Figure 7. This figure is a sectional view on a somewhat larger scale than Figure 1, showing how frames 1b-2b-3b and 4b-5b-6b engage the inner folds of the cuff of the two legs Ta and Tb of a pair of trousers. As will be seen, the vertical sections 1b, 6b, 3b, and 4b are of a length somewhat greater than the width of the cuff on the trousers, so that these vertical sections extend from the bottom of the fold beyond the edge of

the cuff. As will be seen in Figures 5 and 7, the vertical sections 3b and 4b, which engage the inner edges of the vertical folds of the cuffs, are joined together by the loop b. In a similar manner, vertical sections 3a-4a engage the inner edges of the vertical folds of the cuffs on the opposite side of each trousers leg, and these two sections are joined together by the loop a. The horizontal sections 2a, 5a, 2b and 5b are arranged to engage the inner edge of the bottom fold of the cuffs and serve as supporting sections for the trousers. These sections are of appreciable length so there will be no tendency for the frames to puncture the material of the trousers or to distort the material, while the trousers are suspended on the frames. The weight of the trousers is carried by the horizontal sections, and due to the resiliency of the arms Fa and Fb, and also of the coil sections Ea, Eb, the two arms Fa and Fb are bent downwardly under the weight of the trousers, thereby causing the vertical sections 3a-4a and 3b-4b to separate or spread apart so that the vertical sections engage against the inner edges of the vertical folds of the cuff and maintain the cuffs of the trousers under tension. This action tends to maintain the trousers in properly creased condition.

As will be seen from Figure 5, the two parallel frames supported on each of arms Fa and Fb assume the form of hook elements having their open sides facing downwardly, each hook being formed of two parallel strands having an outer section (3a-4a and 3b-4b) arranged vertically to engage the inner edges of the vertical folds of the cuffs, and each hook having a horizontal portion or section (2a-5a and 2b-5b) for engaging the inner edges of the bottom folds of the cuffs.

When the hanger is not in use, it may be folded into a comparatively small space by hooking the two arms over the looped or hooked portions Ca and Cb formed on the shank D as shown in Figures 6 and 8. The showing in Figure 8 is on a somewhat larger scale than in Figures 5 and 6. The provision of the loops Ca and Cb for folding the hanger is not essential to the present invention, and these loops may be omitted if desired.

Various other modifications will occur to those skilled in the art. For example, instead of twisting the strands together, I may employ welding to secure the parallel strands to each other at the places where the wires have been shown twisted together in the drawing, or the wires may be fastened together in any other suitable manner as by a suitable sleeve embracing the two parallel strands at the places where the wires are to be secured together. It will also be understood that the looped portions 11d, 12d and Ea, Eb need not be provided where it is possible to secure the desired resiliency in the arms themselves.

I do not intend to limit myself to any particular procedure in forming the hanger; the shank portion may be formed first and the arms last, or vice versa. It may be formed by hand or by machine, as desired.

I claim:

1. A trousers hanger including a vertical shank member having means at the upper end thereof for suspending the same in substantially a vertical position, a pair of arms secured to the lower end of said shank and extending in opposite directions therefrom, each of said arms being formed of two substantially parallel strands of resilient wire secured to the lower end of said shank and joined at their outer ends to form a loop, and each arm comprising an inner section

extending outwardly and upwardly from the lower end of said shank, an intermediate section extending horizontally outwardly from said first section, and an end section embodying said loop extending downwardly from said intermediate section, the wire strands forming one side of the two arms being arranged in a common plane lying on one side of said shank, and the strands forming the other sides of the two arms being arranged in a common plane parallel with said first plane and lying on the opposite side of said shank.

2. A trousers hanger including a vertical shank member having means at the upper end thereof for suspending the same in substantially a vertical position, an arm structure comprising a pair of parallel, inverted U-shaped wire frames arranged at one side of said shank with their planes on opposite sides of the axis of said shank, a second arm structure comprising a second pair of parallel, inverted U-shaped wire frames arranged in alignment with said first pair of frames on the opposite side of said shank, one leg of each frame being positioned adjacent said shank

15

5 member and the other leg thereof being spaced outwardly from said shank member, the outermost legs of each pair of frames being joined together at their lower ends to form a loop lying in a plane at right angles to the planes of said frames, and resilient supporting means connecting the lower end of each of the innermost legs of each frame to the lower end of said shank.

3. A trouser hanger according to claim 2 where-
10 in said resilient supporting means comprises a loop section included in each frame of said hanger at the point of connection with said shank.

Certificate of Correction

Patent No. 2,494,400

January 10, 1950

EDWIN T. McNUTT, JR.

It is hereby certified that errors appear in the printed specification of the above numbered patent requiring correction as follows:

Column 2, line 10, for "wires 10b and 10b" read *strands 10a and 10b*; line 41, for "V-shaped" read *U-shaped*;

and that the said Letters Patent should be read with these corrections therein that the same may conform to the record of the case in the Patent Office.

Signed and sealed this 16th day of May, A. D. 1950.

[SEAL]

THOMAS F. MURPHY,
Assistant Commissioner of Patents.
